United States Patent Office.

B. F. PEASLEE, OF LAKE VILLAGE, NEW HAMPSHIRE.

Letters Patent No. 63,746, dated April 9, 1867.

IMPROVEMENT IN KNITTING-MACHINE NEEDLES.

The Schedule referred to in these Letters Patent and making part of the same.

TO ALL WHOM IT MAY CONCERN:

Be it known that I, B. F. PEASLEE, of Lake Village, in the county of Belknap, and State of New Hampshire, have invented an improved Knitting-Machine Needle; and I do hereby declare that the following is a full and exact description thereof, reference being had to the accompanying drawings, making part of this specification—

Figure 1 being a top view of the latch of the needle.

Figure 2, a view of the latch in perspective.

Figure 3, a view of the whole needle in perspective.

Like letters designate corresponding parts in all of the figures.

My invention is an improvement in the latch needle, and consists in forming journals on the latch as a part of the same or permanently fixed thereto.

These journals α are to be used in place of the ordinary rivet or pivot, which is inserted loosely through a hole in the latch, and riveted in corresponding bearings in the sides of the needle. Such rivets are very liable to work loose, and by projecting at one end to make bad work in knitting, or to work out and disengage the latch. But by my invention the journals α being formed as a fixed part of or attached fixedly to the latch A, there is no working loose, and consequently no liability whatever of injuring the work, nor of the needle's getting out of repair, except by ordinary breaking. The journals α are preferably stamped out of the metal of the latch itself in forming the same, but they may be inserted as a pin through the latch, and soldered or brazed therein or otherwise fixedly attached thereto. The latch is inserted in the needle B, by spreading out the sides of the latch slot, which after the insertion spring in again and retain the latch in place.

What I claim as my invention, and desire to secure by Letters Patent, is—

Forming fixed journals α , on the latch of the needle, substantially as and for the purpose herein specified.

The above specification of my improved knitting-machine needle signed by me this 10th day of November,

1866.

B. F. PEASLEE.
